PROCESS OF MAKING BAGS

Adolph Potdevin, Garden City, N. Y., assignor to
 Potdevin Machine Company, Brooklyn, N. Y., a
 corporation of New York

Application December 15, 1932, Serial No. 647,298

2 Claims. (Cl. 93—35)

This invention is directed to a process for the making of bags, and one of the objects of my invention is the provision of a method which is particularly well adapted for the making of bags from cellulose, glassine and such materials which are very difficult to handle in bag making machines in the ordinary way.

In the drawing accompanying this application:

Fig. 1 is a diagrammatic plan view of an embodiment of the invention;

Fig. 2 is a sectional elevational view of Fig. 1; and

Fig. 3 is a view in perspective of the completed bag.

In illustrating the invention I have attempted to illustrate more particularly the various steps or operations through which the bag-making material passes in the making of a bag rather than the details of the machine by which the material is handled, inasmuch as such machines may take various forms.

Referring to the drawing in detail, the material from which the bags are to be made is taken continuously from a supply roll 1, the material in web form designated 2 passing from this supply roll about guide roller 3 to an adhesive-applying disc 4 where a stripe of adhesive shown at 5 in Fig. 1 is applied to the face of the web adjacent one edge thereof.

After the application of this adhesive the material still in web form is passed between rollers 6 and 7. The roller 7 carries an arcuate slitter 8 and as the web 2 passes between the rollers the slitter cuts arcuate slits 9 in the center of the web at regularly spaced intervals.

The web then passes through tubing mechanism 10 to be tubed. The tubing mechanism may take the usual form employed in bag making machines and hence has been shown merely diagrammatically.

The tube as formed passes continuously through forwarding rollers 11 and past cutting off mechanism where it is divided into bag lengths. This cutting off mechanism comprises a fixed member 12 and rotatable striker bar 13.

In severing or dividing the tube into bag lengths, one of which is shown at 14, it is to be noted that the lower wall of the leading end is severed transversely to the ends of the arcuate slit 9 to provide a projecting tab 15, while the upper wall of the leading end is cut or severed all the way across as shown at 16 back of or to the rear of the end of the lower wall, so that the lower wall projects beyond the upper wall in the form of a flap 17 carrying the tab 15.

The trailing end of the bag length is complementary to the leading end, the upper wall extending below the lower wall to form a flap 18 while the trailing end of the lower wall is pro-

vided with a notch 19 complementary to the tab 15 at the other end of the bag length.

The bag lengths are continuously forwarded between another pair of rollers 20 to a second severing mechanism comprising fixed member 21 and rotatable shear bar 22, the latter being so timed as to cut off the flap 18 at the trailing end of the bag length, i. e., square the trailing end of the bag length so that this end of the bag length is simply left with the notch 19 in it.

The bag length, which is now as shown at 23 in Fig. 1, has adhesive 24 applied to the upper wall thereof at its leading end and the flap 17 and tab 15 are then folded over along the line 25 upon the upper wall of the bag length to bottom the bag as shown in Fig. 3.

What I claim is:—

1. In the making of bags, the method which comprises continuously advancing the bag material in the form of tubing with arcuate slits 20 spaced at regular intervals lengthwise of the tubing in one wall thereof, severing the tubing into bag lengths in predetermined relation to said slits to provide one wall of the leading end of the bag length with a tab-carrying projecting flap, and 25 the trailing end of said wall with a complementary thumb notch, and to provide the trailing end of the opposite wall of the bag length with a flap extending the width of the bag length and projecting beyond the thumb-notched wall, trimming the trailing end of the bag length back of the flap so as to remove the flap and trim the trailing end of both walls of the bag length, so that the edges of this end of the bag length are 30 smooth and unserrated, and then folding over 35 the tab-carrying flap at the leading end of the bag length to bottom the bag.

2. In the making of bags, the method which comprises continuously advancing the bag material in web form, forming arcuate slits in the advancing web, said slits being spaced at regular intervals lengthwise of the web, tubing the slitted web, severing the tubing into bag lengths in predetermined relation to said slits to provide one wall of the leading end of the bag length with a tab-carrying projecting flap, and the trailing end of said wall with a complementary thumb notch, and to provide the trailing end of the opposite wall of the bag length with a flap extending the width of the bag length and projecting beyond the thumb-notched wall, trimming the trailing end of the bag length back of the flap so as to remove the flap and trim the trailing end of both walls of the bag length, so that the edges of this end of the bag length are smooth and unserrated, and then folding over the tab-carrying flap at the leading end of the bag length to bottom the bag.

ADOLPH POTDEVIN. 60
